UNITED STATES PATENT OFFICE.

PHILIP FAIRCLEUGH DOUGLAS, OF MINNEDOSA, CANADA.

BOBBIN WINDER.

1,428,813.

Specification of Letters Patent.

Patented July 18, 1922.

Application filed February 16, 1921. Serial No. 445,529.

To all whom it may concern:

Be it known that I, PHILIP FAIRCLEUGH DOUGLAS, a subject of the King of Great Britain, residing at the town of Minnedosa, 5 in the Province of Manitoba, in the Dominion of Canada, have invented certain new and useful Improvements in Bobbin Winders, of which the following is a specification.

This invention refers to improved means 10 for winding the bobbins of sewing machines, particularly the heavy duty machines used by shoe makers for patching. Prior to the present invention the entire attention of the operator was required to be given to the operation when it became necessary to wind a 15 bobbin, it being even necessary to hold the spool from which the thread was drawn, and to guide the same as it was wound upon the bobbin. The object of the present invention 20 is to provide means whereby after the end of the thread has been connected with the bobbin, no further attention from the operator is required, the several acts of winding the thread upon the bobbin, evenly distributing 25 the said thread as it is wound and the stopping of the bobbin when fully wound, being automatically performed.

With this object in view the invention resides in the novel construction and combination 30 of parts hereinafter first fully described in the following specification and then more particularly pointed out in the appended claims, reference also being had to the drawings forming part hereof in which similar 35 characters of reference indicate similar parts throughout the different views, and in which—

Fig. 1 is an end elevation of a portion of 40 a sewing machine showing the device connected therewith and independently belt driven from the shaft of the sewing machine.

Fig. 2 is a front elevation of the device 45 and its connection with the sewing machine.

Fig. 3 is a plan sectional view taken upon 50 the plane of the line 3—3 in Fig. 1.

Fig. 4 is the bobbin winding apparatus as 55 viewed in the direction indicated by the line 4—4 in Fig. 1.

Fig. 5 is an end elevation of the device in 60 connection with a sewing machine, this being a modification in that the bobbin winder is driven by friction from the sewing machine belt.

Fig. 6 is a front side elevation of the device 55 shown in Fig. 5.

Fig. 7 is an enlarged top plan view of the 60 spool holding part of the mechanism and the thread tensioning device thereon.

Fig. 8 is an enlarged end elevation of the 65 spool holder and tensioning mechanism viewed in the direction indicated by the line 8—8 in Fig. 7.

Fig. 9 is an enlarged end elevation of the 70 bobbin winding mechanism, and showing the clamp used to detachably connect it with the sewing machine.

Fig. 10 is a rear side elevation of the 75 bobbin winder as viewed in the direction of the line 10—10 in Fig. 9.

Fig. 11 is an end view of the thread distributing and bobbin stopping member.

Fig. 12 is a side view of the member 80 shown in Fig. 11.

In the present disclosure the device is 85 shown in suitable form for detachable connection with sewing machines of standard design, so that users of such machines may obtain the benefits of the invention without any change whatever in the construction of 90 their said machines, it will however be obvious to persons familiar with the art that the mechanism can be advantageously adapted in new constructions to form an integral part of the sewing machine structure. 85

In the drawings A indicates so much of a 95 sewing machine of standard design as is necessary to show the connection of the present device therewith, while B indicates the bobbin winder proper and C the holder for the spool from which the bobbin is fed.

The part B comprises a base member 13 100 detachably secured to the top or table 14 of the sewing machine by a clamp 15 which passes down through the belt hole 16 in the top to engage the under side of the said top.

A pedestal 17 rises from the base member 13, and a spindle 18 is rotatably journaled in the pedestal, the spindle being preferably of slightly tapered conformation so that a 105 bobbin 19 may be placed thereon, and held by frictional contact to rotate in unison with the spindle, a pulley 20 on the spindle connected by a belt 21 with the shaft 22 of the stitching mechanism of the sewing machine A, providing means for the rotation of the spindle.

A member 23 has its lower end connected

for partial rotation with the base 13 of the part B by means of a pivot 24 the said member extending vertically for a portion of its length then curving over the top to 5 form a hood 25 over the bobbin 19, the extremity of the curved or hood portion being bifurcated to form an inverted V shaped opening 26 in the face of the hood, the apex of the opening 26 being continued to form 10 an upwardly extending slit 27.

The arm supporting pedestal 28 of the sewing machine B, is mounted upon a plurality of legs 29, and the spool holder C comprises a base 30, adapted to lie flat upon 15 the top 14 of the sewing machine, the base 30 being shaped to provide a recess 31 adapted to snugly receive one of the legs, 29 and to be thereby removably maintained in position upon the top 14.

20 A spindle 32 projecting vertically from the base 30, is adapted to receive a spool of thread 33 rotatively thereon, and a plurality of members 34 projecting upwardly from the base 30 in irregular or zig zag formation, 25 have their upper ends shaped to form eyes 35, through which the thread 36 passes from the spool 33 to the bobbin, the irregular disposition of the members 34 compelling a tortuous course of the tread and creating a 30 suitable tension of the same, for bobbin winding purposes.

37 indicates a stop which serves to restrict the rotation of the member 23 in one direction.

35 When it is desired to wind a bobbin, the end of the thread 36 is drawn down into the slit 38 usually found in the flanged end of a bobbin for this purpose. The bobbin is then placed upon the spindle 18 and the sewing machine started the thread passing into 40 the bobbin by way of the opening 26 in the face of the member 23 and being guided thereby the said member being free to move upon its pivot 24 from side to side. As the

45 winding proceeds and the bobbin fills the thread rises higher and higher in the opening 26 until finally when the bobbin is full it reaches and jams in the slit 27 thus stopping rotation of the bobbin and spindle 18. 50 As the power required to wind the bobbin is of course very small the belt 21 is run very slack so that when rotation of the bobbin ceases the belt may either continue to run idly over the pulley 20, or it may cease 55 movement and stand idle upon the shaft 22.

When the filled bobbin is required for use in the sewing machine the thread is cut by the operator, the member 23 is rotated on its pivot 24 into the position indicated by the 60 dotted lines in Fig. 4, when the bobbin may be removed from the spindle.

The variation shown in Figs. 5 and 6 refers only to the method of driving the spindle, a friction pulley 38 being mounted 65 on the said spindle in driving contact with

the belt 39 by which the sewing machine itself is driven. In all other respects the devices are similar and when the bobbin is full the pulley 38 which rests lightly against the belt, simply stands still until the bobbin 70 is removed.

From the foregoing description it will be seen that the member C provides for the holding of the spool from which the thread is drawn to the bobbin under tension by 75 reason of its passage through the eyes 35 of the members 34, while the member 23 of the part B provides in simple form the means by which the thread is distributed on the bobbin, and the said bobbin prevented from 80 further rotation when fully wound.

Having thus fully described my said invention what I claim is—

1. A device of the kind described comprising a suitably supported spindle adapted to receive a bobbin in intimate relation therewith, a member forming a hood over the bobbin, an opening in the face of the hood, means to feed thread to the bobbin through the opening in the hood, means to rotate the spindle 85 from the sewing machine to fill the bobbin and a slit upwardly directed from the opening in the hood in which the thread jams to stop rotation of the spindle when the bobbin 90 is full. 95

2. A device of the kind described comprising a suitably supported spindle adapted to receive a bobbin in frictional engagement therewith, a member pivotally mounted for restricted lateral movement forming a hood over the bobbin, an inverted V-shaped opening formed in the extremity of the hood member permitting entrance of the thread to the bobbin, means to rotate the spindle from the sewing machine to fill the bobbin, and a 100 slit upwardly directed from the apex of the opening in the hood in which the thread jams when the bobbin is full to stop rotation of the spindle. 105

3. A device of the kind described comprising a base, and means to removably clamp the base to a sewing machine top, a pedestal rising from the base, a spindle suitably supported from the pedestal adapted to receive a bobbin, a member pivoted to the structure 110 and having a portion shaped to form a hood normally positioned over the bobbin, an inverted V-shaped opening formed in the extremity of the hood constituting an entrance for thread to the bobbin, means to rotate the 115 spindle from the sewing machine to fill the bobbin and a slit connected with the opening in the hood in which the thread jams when the bobbin is full to stop rotation of the spindle. 120

4. A device of the kind described comprising a structure, shaped to form a support for a spindle, a spindle rotatably supported from the structure, adapted to receive a bobbin, means to rotate the spindle from the 125 130

sewing machine, and means to evenly distribute thread to the bobbin, and to stop rotation of the spindle when the said bobbin has been filled, said last means comprising 5 a member having a vertical portion pivoted to the structure for limited lateral movement merging into a curve constituting a hood over the bobbin, the hood portion being bi-

furcated to provide an upwardly converging opening in the extremity of the hood portion, through which the thread passes as it is wound upon the bobbin, and a slit extending up from the opening, in which the thread jams when the bobbin is full. 10

In testimony whereof I affix my signature. 15
PHILIP FAIRCLEUGH DOUGLAS.
